(57) **CLAIM**

The ornamental design for a backpack, as shown and described.

DESCRIPTION

FIG. 1 is a front perspective view of a backpack showing the claimed design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines in the Figures show portions of the backpack that form no part of the claimed design.

The hatched lines in the figures show shading and not surface ornamentation.

1 Claim, 7 Drawing Sheets

FIG. 1

FIG. 4

FIG. 5

FIG. 6

FIG. 7

UNITED STATES PATENT AND TRADEMARK OFFICE
CERTIFICATE OF CORRECTION

PATENT NO. : D771,372 S
APPLICATION NO. : 29/515308
DATED : November 15, 2016
INVENTOR(S) : Kelly et al.

Page 1 of 1

It is certified that error appears in the above-identified patent and that said Letters Patent is hereby corrected as shown below:

On the Title Page

In Column 1, please remove the title “Related U.S. Application Data” and item (63) paragraph, “Continuation of application No. 29/515,092, filed on January 20, 2015.”.

In Column 2, item (57) the claim should be amended from “The ornamental design for a backpack, as shown and described” to --The ornamental design for a backpack as shown and described.--.

In Column 2, the Description section, please remove lines 9 – 10.

Signed and Sealed this
Eleventh Day of April, 2017

Michelle K. Lee
Director of the United States Patent and Trademark Office
